FIG. 1 is a front perspective view of an exhalation port for a breathing circuit, showing our new design.

FIG. 2 is a rear perspective view thereof.

FIG. 3 is a front view thereof.

FIG. 4 is a rear view thereof.

FIG. 5 is a sectional view thereof taken along line 5-5 of FIG. 3.

FIG. 6 is a left side view thereof.

FIG. 7 is a right side view thereof.

FIG. 8 is a top view thereof; and,

FIG. 9 is a bottom view thereof.

The broken lines in the drawings illustrate portions of the exhalation port for a breathing circuit which form no part of the claimed design.

The references to “left,” “right,” “front,” “rear,” “top,” and “bottom” in the figure descriptions are not meant to require certain in-use orientation; the exhalation port according to the claimed design may be used in any orientation.

1 Claim, 4 Drawing Sheets
